Frank J. Lovin,

INTRODUCTION

WITNESS:

INVENTOR
BY *Victor J. Evans*

ATTORNEY

UNITED STATES PATENT OFFICE.

FRANK J. LOVIN, OF MAHNOMEN, MINNESOTA.

BLADE HOLDER.

Application filed September 14, 1925. Serial No. 56,361.

To all whom it may concern:

Be it known that I, FRANK J. LOVIN, a citizen of the United States, residing at Mahnomen, in the county of Mahnomen and

5 State of Minnesota, have invented new and useful Improvements in Blade Holders, of which the following is a specification.

My present invention has reference to a holder for razor blades and aims to provide 10 a simple construction whereby the blades may be effectively held for holding or for cutting purposes.

To the attainment of the foregoing the improvement consists in the improvement 15 as hereinafter described and definitely claimed.

In the drawings:—

Figure 1 is a side elevation of the improvement.

20 Figure 2 is a bottom plan view thereof. Figure 3 is a sectional view on the line 3—3 of Figure 1.

Figure 4 is a sectional view on the line 4—4 of Figure 1.

25 Figure 5 is a perspective view of the holder.

Figure 6 is a similar view looking toward the outer end of the handle.

In carrying out my invention I make use 30 of a tubular handle 1 which is preferably of metal. The handle 1 is closed at one end, but has its other end open and the said open end is slit longitudinally for a determined distance to provide what I will term 35 jaws 2—2. Inward of the jaws the handle is grooved longitudinally, as at 3, and these grooves afford an effective grip for the thumb of the operator when holding a razor blade in a manner which will presently be 40 apparent.

The clamp for a safety razor blade 4 is broadly indicated by the numeral 5. The clamp is constructed of spring metal which is centrally bent and rounded upon itself to 45 provide a head 6 and parallel sides 7. The sides are, of course, spaced one away from the other, and one of the sides 7 has spaced longitudinal slits which are intersected by a central transverse slit and the metal bounded 50 by these slits is bent first outwardly, as at 8, and from thence inwardly, as at 9. The ends 9 are received in the opening 10 provided by the referred to slits. These ends bear against the plate, preferably of 55 light material, which is indicated by the numeral 11.

In operation the clamp 5 has the blade 4 inserted between the sides 7 thereof, and disclosed most clearly in Figures 2, 3 and 4 of the drawings. Thus one side of the blade 60 contacts with the outer face of the plate 11. The device is then moved longitudinally between the jaws 2 of the handle 1. The spring fingers 8 will contact with the lower edge provided by one of the jaws 2, and by virtue of such contact the said spring fingers will be moved into the opening 10, to cause their portions 9 to press against the plate 11, and force the said plate and the blade 4 against the second side 7 of the clamp, thus 70 effectively holding the blade and clamp on the handle.

Because the handle is rounded and the head 6 of the clamp 5 is likewise rounded, and both of these rounded portions are 75 brought, at times to contact with the strop, when a razor is to be honed or sharpened, the device, as a whole may be alternately turned from side to side on the said strop in an easy and expeditious manner. The improvement as previously inferred may serve 80 as a handle and clamp for a razor blade when the latter is employed for cutting, and the simplicity and advantages of my construction will be perfectly apparent to 85 those skilled in the art to which such invention relates.

Having described the invention, I claim:—

In a device for the purpose set forth, a 90 handle comprising a tubular member having one end slotted longitudinally to provide spaced jaws, said handle inward of the jaws being grooved longitudinally, a clamp comprising a spring metal plate which is centrally rounded upon itself to form the same with a head, side plates extending in parallelism from the head, one of said side plates having an opening therethrough and being formed with outwardly rounded inwardly 95 extending fingers disposed opposite the opening, a plate between the sides, contacted by the fingers, the second side and the said plate designed to receive a razor blade therebetween and the said fingers adapted to be contacted by one of the jaws of the handle and to be sprung by virtue of said contact to exert a pressure against the plate to cause the latter to exert a like pressure against 100 the blade.

In testimony whereof I affix my signature.
FRANK J. LOVIN,
